UNITED STATES PATENT OFFICE.

ELMER J. BRYANT, OF WOONSOCKET, RHODE ISLAND, ASSIGNOR TO THE TAFT-PEIRCE MANUFACTURING COMPANY, OF WOONSOCKET, RHODE ISLAND, A CORPORATION OF RHODE ISLAND.

TOOLMAKER'S ADJUSTABLE KNEE.

1,355,809.

Specification of Letters Patent. Patented Oct. 19, 1920.

Application filed August 27, 1918. Serial No. 251,708.

To all whom it may concern:

Be it known that I, ELMER J. BRYANT, a citizen of the United States, and a resident of the city of Woonsocket, in the county of Providence, State of Rhode Island, have invented new and useful Improvements in Toolmakers' Adjustable Knees, of which the following is a specification.

This invention relates to small tools, and more particularly to a toolmaker's adjustable knee.

The principal object of the present invention is to provide a knee or angle iron provided with an adjustable bed which may be accurately set to a predetermined plane which may be the plane of the supporting base for the tool.

A further object of the present invention is an adjustable knee as specified and wherein the knee comprises a pair of base members having plane faces thereon disposed at a predetermined angle and with strengthening webs extending between the base members in such manner as to form supports for the arms of an adjustable bed, so that the bed may be set at any predetermined angle relatively to the said plane surfaces.

A still further object of the present invention is an adjustable knee as specified, and wherein the plane surfaces are disposed at right angles to each other with the pivots for the arms of the adjustable bed mounted on a line bisecting the said right angle, and with the face of the bed disposed at a right angle to the axis of the pivoted arms so that the inclination for angle of the face of the bed relative to one of the plane surfaces will be complementary to the angle which the inclination of the face of the bed makes with the plane of the other surface.

Another and important object of the present invention is a knee of the character specified, wherein an extension comprising an accurately ground cylinder is provided on the pivot bolt for the arms of the bed and with the axis of the cylinder coincident with the axis around which the arms rotate, and wherein an accurately ground cylinder of identically the same diameter is adapted to be carried by the end of the bed in such manner that a plane joining the axes of the said cylinders will be at right angles to the surface of the bed and will include the axis around which the arms rotate. The

said constructions are such that by measuring the heights of the said cylinders from one of the base planes, the natural sine of the angle which the plane of the bed surface makes with the opposite base plane may be accurately determined and the bed of the knee may be accurately positioned to any required angle by referring to a table of natural sines and setting the cylinders accordingly.

Another object of the present invention is a knee of the character specified wherein the ends of the bed terminate in substantially the same plane as the ends of the base, whereby the knee may be set on end as well as on one of the bases.

A further object is a knee of the character specified wherein the sine measure cylinder carried by the bed is removable in order that the bed may be positioned on end as stated.

A still further object of the present invention is a knee of the character specified wherein the bed extends farther to one side of the center line of the arms than to the other side, so that when the bed is positioned at an extreme limit in one direction the edge of the bed is substantially coincident with the plane of the adjacent base, and when the bed is positioned at its other limit the other edge of the bed extends beyond the plane of the adjacent base.

Other and further objects will in part be obvious and will in part be pointed out hereinafter in the specification following by reference to the accompanying drawings wherein like parts are indicated by like characters throughout the several figures thereof.

Figure 1 is a perspective view of the end of the knee provided with the vernier scale.

Fig. 2 is a perspective view showing the end of the knee which is provided with sine determining fixtures.

Fig. 3 is an end view illustrating the method of obtaining the sine of the angle of the face plate.

Fig. 4 is a perspective view showing the bed carrying a piece of work.

Fig. 5 is a back view of the knee.

Heretofore in the art where it has been desired to mill or otherwise produce a surface or an opening with a predetermined angular relation to some other surface or opening in the work, it has been common to

- mount up the work on a stationary elbow or knee. If only a few pieces of work were desired to be made each piece was separately positioned and clamped in its desired angular relation. It has been the practice, where a number of such parts are to be made, to provide a specially formed stationary elbow or knee on which the work would be positioned. There have also been provided in the art certain types of adjustable surface plates which could be raised or lowered at one edge by jack screws to test or hold work wherein slight angular adjustment could be obtained.
- 15 The present invention brings into the art a new tool by means of which work may be tested or may be supported while being formed and wherein any inclination from zero to 90 degrees may be given to the work.
- 20 At the same time the tool is provided with accurate measuring devices so that the inclination of the work may be very accurately determined. The tool is constructed also with the view of producing rigidity and
- 25 strength so that the work positioned thereon is rigidly securely and accurately held while being milled or formed by a machine tool or while being tested by measuring instruments.
- 30 Referring now to the drawings, the supporting frame comprises an angular-shaped base having one portion 1 provided with a plane surface 2 which is angularly disposed to the plane surface 4 on the portion 5, and
- 35 preferably the angle between the planes 2 and 4 shall be a right angle. A pair of strengthening webs 6 and 7 are provided at right angles to the portions 1 and 5, preferably with the edges of the webs curved to
- 40 comprise quadrants of a circle. The portions 1 and 5 are provided with side openings 8 through which stub bolts may be placed to secure the tool in position on the bed of a machine tool such as a milling
- 45 machine. The webs 6 and 7 are drilled and provided with bushings, preferably steel or bronze bushings 9, through which extend heavy pivot bolts 10 and 11 that comprise the supports for the arms 12 and 14 of the
- 50 work table or bed 15. It will be noted (see Fig. 5), that the arms 12 and 14 are both on the right side of the webs 6 and 7. This construction makes the distance between the arms the same as the distance between the
- 55 webs. This facilitates accurate finishing of the respective engaging faces, as well as providing symmetry of these parts. Preferably dowel pins 16 extend through the heads of the pivot bolts 10 and 11 to prevent turning of the bolts. The pivot bolts 10 and 11 carry hexagonal nuts 17 which are seated against friction washers 18 that are provided with keys 19 which prevent these washers from rotating on the pivot bolts. The web 6
- 60 carries a quadrant scale 20 divided in degrees,

and the bed carries a vernier 21 which cooperates with the quadrant scale 20, whereby readings may be obtained to the accuracy of five minutes. The web 7 is provided with an arc-shaped opening through which extends the clamp bolt 22 that is carried by the arm 14.

By loosening and tightening the hexagonal nut 24 on the clamp bolt 22 the bed 15 may be adjusted and then securely held in any predetermined position. The bed is provided with a plurality of undercut grooves 25 in which stub bolts may be inserted for clamping a piece of work such as 26 (Fig. 4) in position on the bed. The pivot bolt 10 is provided with an accurately ground cylindrical extension 27 and the end of the bed is provided with an accurately ground bushing 28 in which a carefully fitted cylindrical plug 29 is adapted to be carried. This plug 29 is removable in order to enable the tool to be set on end. A plane which includes the axes of the cylindrical extension 27 and the cylindrical plug 29 is at right angles to the plane of the surface of the bed 15. The cylindrical extension 27 and the cylindrical plug 29 form convenient means by which the inclination of the surface of the bed to either of the plane surfaces 2 or 4 may be easily determined by use of a height gage and the table of natural sines, as will hereinafter be explained. In order to facilitate computations, the distance between the axes of the cylindrical extension 27 and the cylindrical plug 29 preferably comprises a 10 units, a multiple of 10, or a factor of 10. That is, the distance might comprise 10 inches or 10 centimeters, or multiples or factors of such units of measure.

To accurately determine an angle which the plane of the bed 15 makes with either of the plane surfaces 2 or 4, the device may be set on a plane surface, such as a surface plate 30 (Figs. 3 and 4), and the height X between the surface plate and the lowermost portion of the cylindrical extension 27 then carefully measured by a height gage 31. In the same manner the distance between the lowermost portion of the plug 29 and the surface plate 30 may be determined. Then since the hypotenuse A—B of the triangle A—B—C is the known distance between the axes of the cylindrical members 27 and 29 and if this distance be ten units, the height B—C is equal to the total distance between the plug 29 and the surface plate 30, minus the distance Y, which is the same as X. This is a direct reading on the height gage of the natural sine of the angle W. This angle W is identically the same as the angle Z which the plane of the bed 15 makes with the plane surface 2.

Realizing that my invention will be carried out in structures other than that specifically disclosed herein, I desire that the

present disclosure be understood as illustrative and not to be taken in the limiting sense.

Having described my invention what I claim is:

1. In a device of the character described the combination of a base having angularly disposed portions provided with plane surfaces meeting at right angles, a work-supporting bed, arms extending from the under portion of said bed and pivoted to said base, a cylindrical member mounted adjacent said pivots with the axis of said cylindrical member coincident with the axes of the pivots, another cylindrical member adapted to be carried by said work-supporting bed in such manner that a plane joining the axes of the said cylindrical members is at right angles to the surface of the work-supporting bed, and with the distance between the axes of the said cylindrical members being such that the natural sine of the angle which the plane of the bed makes with one of the first mentioned plane surfaces may be read directly on the scale of a suitable height gage.

2. In a device of the character specified the combination of a base having angularly disposed portions provided with intersecting plane surfaces, strengthening webs disposed at substantially right angles to the said base portions, a work-supporting bed provided with arms pivoted to the said webs, securing means whereby said bed may be locked in predetermined angular relation to the said plane surfaces, a cylindrical member having its axis substantially coincident with the axis of the pivots of said arms, a second cylindrical member spaced apart from the first mentioned cylindrical member in such manner that a plane joining the axes of the said cylindrical members is at substantially right angles to the surface of the work-supporting bed and with the axes of said cylinders spaced apart a predetermined distance in such manner that the difference between the perpendicular distances of the axes of said cylinders from one of the first mentioned plane surfaces corresponds to the natural sine which the plane of the bed makes with the other first mentioned plane surface.

3. A device of the class described comprising the combination of a base having angularly disposed portions provided with base plane surfaces intersecting at a right angle, a work-supporting bed pivoted to the said base in such manner that the axis of the said pivot is located in a plane bisecting the right angle between the said plane surfaces, a cylindrical member mounted in such manner that its axis is coincident with the said pivotal axis, a second cylindrical member of identically the same diameter as the first mentioned cylindrical member

and located in such manner that a plane including the axes of the said members will be at right angles to the plane of the work-supporting bed, and means to lock said work-supporting bed in predetermined angular relation to the base planes whereby the angle which the surface of the work-supporting bed makes with one of said base plane surfaces is measured by the differences between the perpendicular distances from the other base plane to the peripheries of the said cylinders.

4. A device of the character described comprising the combination of a base member having angularly disposed portions provided with plane surfaces, strengthening webs disposed at substantially right angles to the said portions, a work-supporting bed provided with arms pivoted to said webs, the arms and webs being engaged in pairs and all on the same side relatively to each other, and securing means whereby said bed may be locked in predetermined angular relation to the said plane surfaces.

5. In a device of the character specified, the combination of a base having angularly disposed portions provided with intersecting plane surfaces, strengthening means extending between said portions, a work-supporting bed being provided with arms adapted to be secured to said strengthening means, the engaging pivot portions on the arms being the same distance apart as the engaging pivot portions on the strengthening means and the engaging portions being on the same side relatively to each other, and locking devices whereby the surface of the said supporting bed may be locked in a predetermined angular relation to the said plane surface on the base.

6. A device of the character specified comprising in combination a base member, a work supporting bed pivoted upon said base member in such manner as to be movable around an axis parallel to the plane determined by the base member, means for locking the work supporting bed in predetermined angular relation to said base member, an angle-measuring means comprising a cylinder mounted in such manner that the axis of the cylinder is coincident with the axis of the pivots, a second cylinder of the same diameter as the first mentioned cylinder and spaced apart therefrom so that a line joining the axes of the said cylinders will be at right angles to the work face on the work supporting bed.

7. A device of the class described comprising in combination a base member being provided with a plane surface, supporting means carried by said base member, a work-supporting bed, means comprising pivot bolts for securing said bed to said supporting means in such manner that said bed has a movement of rotation within predeter-

mined limits relatively to the plane of said base, and means to prevent rotary movement of the pivot bolts.

8. A device of the character specified comprising in combination a base member, a work supporting bed pivoted to said base member to be movable on an axis substantially parallel to the plane surface comprising the face of the work supporting table, and measuring means to determine the angle between the work supporting face and the said base said means comprising a cylinder having an axis coincident with the axis of the pivot for the work supporting table, and means adjacent the face for supporting a cylindrical member having identically the same diameter as the said cylinder and with the line joining the axes of said cylinder and said cylindrical member being at right angles to the said work face.

9. A device of the character described comprising in combination a supporting base having a plane surface thereon, a work-supporting table provided with a pair of arms, pivotal means operatively connecting the lower ends of said arms with the said supporting base, the engaging faces on the arms both facing the same direction, clamping means adapted to lock said bed in predetermined angular relation to the plane of said base, and angle measuring devices for determining the angular position in which said bed is locked.

10. In a device of the character specified, the combination of a supporting base provided with a plane surface, a pair of webs secured to said supporting base, a work-supporting table being provided with a pair of arms, means comprising pivot bolts and friction washers for pivoting the lower ends of said arms to said webs, a locking means to prevent rotary movement of the bolts and washers, and means cooperating with one of said arms and one of said webs to lock the said table in predetermined angular relation to the plane on the said base.

11. A device of the character specified comprising in combination, a base having a base plane surface thereon, a work supporting bed pivoted to the said base in such manner as to be rotatable relatively thereto within predetermined angles, a cylinder mounted with its axis coincident with the axis of the pivot for the bed, a second cylinder of exactly the diameter of the first mentioned cylinder and located to move with the bed and in such manner that a plane including the axes of the said cylinders is so disposed relatively to the surface of the said bed that the natural sine of the angle the bed makes with the base plane may be read directly upon a height gage by determining the difference between the distances of the cylinders from a given plane.

ELMER J. BRYANT.
